(57) **CLAIM**

The ornamental design for a rifle chassis locking set, as shown and described.

DESCRIPTION

FIG. 1 is an upper left perspective view of the lower component to the rifle chassis locking set of this invention showing my new design;

FIG. 2 is a left side view of the lower component from FIG. 1;

FIG. 3 is a right side view of the lower component, or opposite view from that shown in FIG. 2;

FIG. 4 is a front axial view of the lower component shown in FIG. 2;

FIG. 5 is a rear axial view of the lower component, or opposite view from that shown in FIG. 4;

FIG. 6 is a top plan view of the lower component from FIG. 2;

FIG. 7 is a bottom plan view of the lower component, or opposite view from that shown in FIG. 6;

FIG. 8 is an upper left perspective view of the upper component to the rifle chassis locking set of this invention;

FIG. 9 is a left side view of the upper component from FIG. 8;

FIG. 10 is a right side view of the upper component, or opposite view from that shown in FIG. 9;

FIG. 11 is a front axial view of the upper component shown in FIG. 9;

FIG. 12 is a rear axial view of the upper component, or opposite view from that shown in FIG. 11;

FIG. 13 is a top plan view of the upper component from FIG. 9;

FIG. 14 is a bottom plan view of the upper component, or opposite view from that shown in FIG. 13;

FIG. 15 is an upper left perspective view of the upper component atop the lower component, assembled together;

FIG. 16 is a left side view of the combined upper and lower components from FIG. 15;

FIG. 17 is a right side view of the combined upper and lower components, or opposite view from that shown in FIG. 16;

(Continued)

FIG. 18 is a front plan, axial view of the combined upper and lower components from FIG. 15;
 FIG. 19 is a rear plan, axial view of the combined upper and lower components, or opposite view from that shown in FIG. 18;
 FIG. 20 is a top plan view of the combined upper and lower components from FIG. 15; and,
 FIG. 21 is a bottom plan view of the combined upper and lower components, or opposite view from that shown in FIG. 20.
 The broken lines in the drawings are used to illustrate unclaimed parts of the invention and form no part of the claimed design.
